PLATE

Louise D. L. Coloman, Los Angeles, Calif.

Application October 14, 1949, Serial No. 5,478

Term of patent 3½ years

(Cl. D44—15)

To all whom it may concern:

Be it known that I, Louise D. L. Coloman, a citizen of the United States, residing in the city of Los Angeles, county of Los Angeles, and State of California, have invented a new, original, and ornamental Design for a Plate, of which the following is a specification, reference being had to the accompanying drawing, forming a part thereof.

Fig. 1 is a top plan view of a plate showing my new design;

Fig. 2 is a side elevational view;

Fig. 3 is an end elevational view;

Fig. 4 is a longitudinal central sectional view; and

Fig. 5 is a transverse sectional view thereof taken on line 5—5 of Fig. 1.

I claim:

The ornamental design for a plate, as shown.
LOUISE D. L. COLOMAN.
